UNITED STATES PATENT OFFICE.

JOHN J. LAASS, OF SYRACUSE, NEW YORK.

WHEEL-HUB.

SPECIFICATION forming part of Letters Patent No. 644,139, dated February 27, 1900.

Application filed June 12, 1899. Serial No. 720,141. (No model.)

To all whom it may concern:

Be it known that I, JOHN J. LAASS, of Syracuse, in the county of Onondaga, in the State of New York, have invented new and useful 5 Improvements in Wheel-Hubs, of which the following, taken in connection with the accompanying drawings, is a full, clear, and exact description.

This invention relates to an improvement 10 in wheel-hubs for bicycles and analogous vehicles.

The chief object of the invention is to produce a wheel-hub which shall be simple, strong, and durable in construction and at the same 15 time inexpensive in its manufacture; and to that end the invention consists, first and essentially, of a wheel-hub comprising a metallic tube forming the body of the hub and having its end portions reduced circumferentially, thereby producing two annular shoulders, spoke-attaching collars embracing said end portions and abutting against said shoulders, and annular wedging retaining-shoulders formed on said end portions and pressing 25 said collars firmly against the abutment-shoulders to rigidly lock the collars to said tube.

Secondly, the invention consists in the process of constructing the herein-described wheel- 30 hub, which is as follows: I provide a piece of tubing of the desired dimensions and circumferentially reduce the end portions of the same, which reductions may be made either by cutting the tube on a lathe or by compressing 35 the tube, and thereby two annular shoulders are produced. I then provide two spoke-attaching collars, preferably of the form of the well-known washer, which collars are placed on said end portions of the tube so as 40 to abut against said shoulders. I then expand said end portions to their original diameters, thereby producing thereon wedging retaining-shoulders which press said collars tightly against the abutment-shoulders, and 45 thus the collars are rigidly locked to the tube, as aforesaid.

Thirdly, the invention consists in the improved manner of attaching the sprocket-wheel to the rear hub; and, furthermore, the 50 invention consists in the novel details of con-

struction, as hereinafter fully described, and set forth in the claims.

In the annexed drawings, Figure 1 is a side view of a front wheel-hub embodying my invention. Fig. 2 is a longitudinal section of 55 said hub. Fig. 3 is a longitudinal section of the tube before the spoke-attaching collars have been applied. Fig. 4 illustrates the means for expanding the end portions of the tube. Fig. 5 is an outer face view of one of 60 the spoke-attaching collars. Fig. 6 is a transverse section of said collar. Fig. 7 is a longitudinal section of a hub, illustrating a modification of the same. Fig. 8 is a longitudinal section of the tube employed in the modified 65 construction. Fig. 9 is an outer face view of one of the spoke-attaching collars employed in the latter construction. Fig. 10 is a transverse section of said collar. Fig. 11 is a longitudinal section of a rear-wheel hub, illustrating 70 my improved sprocket-wheel attachment. Fig. 12 is a vertical transverse section on line X X in Fig. 11. Fig. 13 is a detail face view of a portion of the sprocket-wheel. Fig. 14 is a detail plan view of a portion of the rear hub minus the sprocket-wheel, and Fig. 15 is a longitudinal section 75 of a portion of a rear-wheel hub, illustrating a modification of the sprocket-wheel attachment.

Referring to the drawings, A represents the metallic tube which is employed in my improved construction and constitutes the body of the hub. Said tube has its end portions reduced circumferentially, as indicated at a 85 a, which reductions are made either by cutting the tube, as shown in Fig. 3 of the drawings, or by compression of the tube, as shown in Fig. 8 of the drawings, and in either case producing two annular shoulders b b.

B B denote the two spoke-attaching collars, which I prefer to make in the form of the well-known washer. Said collars are placed on the aforesaid end portions of the tube and made to abut against the shoulders b b and 95 have their inner peripheral edges formed beveled, as indicated at c in Figs. 2, 4, and 6 of the drawings.

The end portions a a of the tube A are expanded after placing the collars B B thereon, 100

- preferably by suitably-shaped mandrels C C, inserted in said ends, thereby forming wedging retaining-shoulders d d, which press firmly against the beveled edges of the collars, and 5 thereby rigidly lock the collars to the tube A. It will be seen that by forming both shoulders b b and d d annular grooves e e are produced, in which the collars are seated, as clearly shown in Figs. 2 and 4 of the drawings. 10 It will also be observed that by said operations annular ribs f f are formed within the tube A, upon which ribs the bearing-cups g g are seated, and are thereby prevented from shifting inward, as shown in Fig. 2.
- 15 In referring to Figs. 7, 8, 9, and 10 of the drawings, illustrating modifications of the hub, the tube A is of a uniform thickness throughout its length and has its end portions reduced circumferentially by compression, as 20 shown at a a, and thereby producing the hereinbefore-described shoulders b b. In reducing the end portions of the tube A by the latter principle the abutment-shoulders b b are not as abrupt as in the preferred construction. 25 Therefore I form the spoke-attaching collars in this case flaring at their inner peripheries, as indicated at h, to conform to the shape of the shoulders b b and to form the bevel c, as clearly shown in Figs. 7 and 10.
- 30 In expanding the end portions of the tube A in the modified construction the mandrels are necessarily made of a slightly-different form (not necessary to be shown) and are inserted in the ends of the tube in manner hereinbefore stated.
- 35 Referring to Figs. 11, 12, 13, and 14 of the drawings, illustrating a rear-wheel hub constructed in the preferred form, D represents the sprocket-wheel, which is formed on its inner periphery with two lugs i i. Said sprocket-wheel is placed onto the end portion of the tube A, with its lugs entering or engaging two longitudinal slots j j, cut in the end of the tube, and is thereby locked to the tube and 45 prevented from turning thereon.
- The extreme end portion of the tube A is screw-threaded externally, to which is applied a screw-threaded ring k, which serves as a nut and bears against the sprocket-wheel to 50 prevent the same from shifting outwardly.
- In Fig. 15 I have illustrated a modification of the sprocket-wheel attachment, in which case the retaining-ring k is formed integral with the bearing-cup g. In this construction 55 it will be seen that the screw-threads can be dispensed with, as the ring is held firmly against the sprocket-wheel by providing the bearing-cup with a tight fit to the tube A.
- What I claim is—
- 60 1. In a wheel-hub, the combination with a metallic tube constituting the body of the hub and provided on each end portion with an annular shoulder produced by circumferentially reducing said end portions, of spoke-attaching collars embracing said end portions and abutting against said shoulders, and wedging

retaining-shoulders pressing the collars firmly against the abutment-shoulders and produced by expansion of said reduced end portions to their original diameters substantially as described. 70

2. In a wheel-hub, the combination with a metallic tube constituting the body of the hub and provided on each end portion with an annular shoulder produced by circumferentially reducing said end portions, of spoke-attaching collars having their inner peripheries flaring and embracing said end portions, and abutting against said shoulders, a bevel produced by said flaring of the collars, and wedging retaining-shoulders pressing against said bevel and produced by expansion of said end portions to their original diameters substantially as described. 80

3. In a wheel-hub, the combination with a metallic tube forming the body of the hub, and having its end portions reduced circumferentially and thereby producing annular shoulders thereon, of spoke-attaching collars embracing said end portions and abutting against said shoulders, wedging retaining-shoulders formed on said end portions and pressing said collars firmly against the abutment-shoulders, annular ribs produced within the tube by the formation of the wedging- 90 shoulders, and the bearing-cups inserted in the ends of the tube and seated on said ribs substantially as described. 95

4. In a wheel-hub, the combination with a metallic tube forming the body of the hub, 100 and having its end portions reduced circumferentially thereby producing annular shoulders, of spoke-attaching collars embracing said end portions and having their inner peripheral edges formed beveled, wedging retaining-shoulders formed on the end portions of the tube and pressing against said beveled edges of the collars to grip the collars between the latter shoulders and abutment-shoulders to lock said collars to the tube, annular ribs produced within the tube by the 105 formation of the wedging-shoulders, and the bearing-cups inserted in the ends of the tube and seated on said ribs substantially as described. 110

5. The combination with a hub provided in one end portion with a series of longitudinal slots and screw-threaded externally on said end, of a sprocket-wheel embracing said end portion and provided on its inner periphery 120 with a series of lugs engaging the aforesaid slots, and a screw-threaded retaining-ring applied to the screw-threaded portion of the hub and bearing against the sprocket-wheel substantially as described. 115

6. The combination with a hub provided in one end portion with a series of longitudinal slots, of a sprocket-wheel embracing said end portion and provided on its inner periphery with a series of lugs engaging the aforesaid 130 slots, the bearing-cup inserted in the end of the hub and having a retaining-ring formed

integral therewith and bearing against the sprocket-wheel substantially as described.

7. The combination with a wheel-hub, of a sprocket-wheel mounted non-revolubly thereon and adapted to be shifted longitudinally to apply it to and remove the same from the hub, a bearing-cup secured in the end of the hub, and a retaining ring or nut formed in-

integral with the cup, and bearing against the sprocket-wheel substantially as described and shown.
